UNITED STATES PATENT OFFICE

STEPHEN D. BAKER, OF NEW YORK, N. Y.

DESIGN FOR A BATHROOM PAPER OR SPONGE HOLDER OR ARTICLE OF ANALOGOUS NATURE

Application filed May 13, 1931. Serial No. 39,833. Term of patent 14 years.

To all whom it may concern:

Be it known that I, STEPHEN D. BAKER, a citizen of the United States, and a resident of New York, in the county of New York and State of New York, have invented a new, original, and ornamental Design for a Bathroom Paper or Sponge Holder or Article of Analogous Nature, of which the following is a specification, reference being had to the accompanying drawings, forming part hereof.

In the drawings:

Fig. 1 is a plan view;

Fig. 2 a front view;

Fig. 3 a side view, and Fig. 4 a perspective view of a bathroom fixture embodying my new design.

I claim:

The ornamental design for a bathroom paper or sponge holder or article of analogous nature, substantially as shown and described.

STEPHEN D. BAKER.
